L. B. GIRARD.

STAPLE.

APPLICATION FILED MAR. 12, 1917.

Patented Jan. 7, 1919.

Inventor:
Louis B. Girard
by Arthur P. Knight
his Attorney.

UNITED STATES PATENT OFFICE.

LOUIS B. GIRARD, OF LOS ANGELES, CALIFORNIA, ASSIGNOR, BY MESNE ASSIGNMENTS,
TO HIMSELF, AND JOHN P. WHITMORE, OF SOUTH PASADENA, CALIFORNIA.

STAPLE.

1,290,173.

Specification of Letters Patent.

Patented Jan. 7, 1919.

Original application filed October 2, 1916, Serial No. 123,436. Divided and this application filed March 12, 1917. Serial No. 154,162.

To all whom it may concern:

Be it known that I, LOUIS B. GIRARD, a citizen of the United States, residing at Los Angeles, in the county of Los Angeles and 5 State of California, have invented a new and useful Staple, of which the following is a specification.

This invention relates to a staple adapted for use in fastening shades on shade rollers, 10 or for similar purposes, and the main object of the invention is to provide a staple that can be cut from a continuous strip of sheet metal, without waste of material and with most efficient use of the metal as regards the 15 strength and holding capacity of the staple.

The present application is a division of my application Serial Number 123,436, filed Oct. 2, 1916, for window shade mounter. In 20 that application, as well as in other applications of my invention, the staple is intended to be driven immediately upon formation thereof, and as a part of the same operation, but my invention, as regards the construction or form of the staple is not dependent 25 on such use thereof, as the staple may be formed as an article of manufacture and applied as a fastening means, by hand or otherwise, at any time after its formation.

In staples for window shades, etc., it is 30 desirable that the staple shall cover and engage with as large a surface of the shade material as possible, in order to distribute the strain on the material as much as possible and prevent the cloth from being torn from 35 the roller by sudden pull or otherwise. My invention provides for such maximum distribution of the gripping action of the staple with a minimum amount of metal used.

My invention also provides a staple which 40 is adapted to fit on the curved surface of the material when on the shade roller, so as to give a closer grip and a neater and smoother finish to the roller.

The accompanying drawings illustrate an 45 embodiment of my invention, and referring thereto:

Figure 1 is a plan view of the blank strip from which the staples are made.

Fig. 2 is a similar view, showing the manner 50 in which the staple prongs are cut from the side of the strip and bent down.

Fig. 3 is a side elevation of Fig. 2.

Fig. 4 is a plan view of the finished staple,

and Figs. 5 and 6 are respectively side and front views thereof, the staple prongs being 55 shown in these figures as bent down but not clenched.

The blank 1 from which the staples are made may consist of a thin ribbon or strip of soft steel, or other sheet metal, and the 60 staples are made therefrom by cutting off sections of the strip in such manner that each cut forms the rear edge of the severed staple and the front edge of the succeeding staple. Each cut leaves the forward end of the strip 65 with a projecting central prong 2, of triangular shape, with a shoulder 3 at each side of said prong, and with oblique edge 4 beyond each shoulder 3 and extending rearwardly and outwardly therefrom to the edge 70 of the strip 1. To form a staple, suitable die means are applied to the strip in such manner as to make oblique cuts 6 at opposite edges of the strip 1, so that the rear edges 75 of these cuts will form the oblique edges 4 for the next staple after the one which is being formed. Concurrently with or subsequently to this cutting operation, the prongs portion 7 which is thus cut from the strip 1 is bent down, as shown in Fig. 3, to form 80 a prong 7 extending down at each side of the strip, and the prong 2 at the forward end of the strip 1 is also bent down as shown in said figure. A V-shaped cut is then made in the strip 1, having its apex at or about the 85 line extending between the side shoulders 3 and at the base of the triangular prong 2, and the lines of said cut extending parallel to the oblique cuts 6 aforesaid, as shown at 10, and terminating in laterally extending 90 cuts 12 which are in line with the bases of the prongs 7. This cut severs the staple already formed and at the same time completes the cutting of the forward edge for the next staple. The said cutting and forming operations are preferably so carried out 95 that the two sides, or branches 11 and 11' forming the top of the staple are bent so as to be convex on top and concave below, thereby enabling the top of the staple to 100 conform more closely to the shape of the material on a cylindrical roller.

The two branches 11 and 11' of the staple top terminate forwardly at the base of the forward prong 2 and are connected only by 105 such prong, and they extend obliquely rear-

ward from such prong to the rear prong, in such manner that each of said branches has the forward prong at its forward inner corner and a rear prong at its rear outer corner. 5 By this means the greatest possible extension or covering capacity of the staple top is obtained, separating the prongs as far as possible and enabling the staple top to cover as much of the material as possible, for a 10 given weight of metal.

It will be understood that when the staple is being made in a stapling machine the prongs 2 and 7 will be driven as they are formed and will be clenched in the goods 15 in such driving operation. My invention relates to the formation of the prongs with relation to the staple top irrespective of whether the prongs are clenched as stated or are left in position shown in Figs. 5 and 6, 20 for use in a subsequent stapling operation.

What I claim is:

1. A staple formed of sheet metal and comprising a forward prong, a top portion formed with two branches terminating forwardly at the base of said prong and extending obliquely rearward and outward there-

from, and a rear prong at the rear outer corner of each branch of the top portion of the staple.

2. A staple formed of sheet metal and 30 formed with two top portions, a downwardly bent prong at the forward ends of said two top portions and a prong at the rear end of each of said top portions, said top portions being separated by a V-shaped cut extending 35 forwardly to the base of the forward prong so that said top portions are united only by said forward prong.

3. A staple comprising a forward prong, two top portions extending rearwardly from 40 said prong and connected solely by the prong, and a rear prong at the rear end of each of said top portions, the outside edges of said top portions extending obliquely rearward and outward and the inside edges 45 extending parallel to the outside edges, from the rear prongs to the forward prong.

In testimony whereof I have hereunto set my hand, at Los Angeles, California, this 26th day of February 1917.

LOUIS B. GIRARD.
